UNITED STATES PATENT OFFICE.

LLOYD V. LEWIS, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,353,250.

Specification of Letters Patent. Patented Sept. 21, 1920.

Application filed January 9, 1920. Serial No. 350,323.

To all whom it may concern:

Be it known that I, LLOYD V. LEWIS, a citizen of the United States, residing at Wilkinsburg, in the county of Allegheny and State of Pennsylvania, have invented certain new and useful Improvements in Railway-Traffic-Controlling Apparatus, of which the following is a specification.

My invention relates to railway traffic controlling systems, and particularly to systems of the type wherein alternating traffic controlling current or currents are supplied to the trackway, and the cars or train are provided with governing apparatus which is controlled by such current or currents. More particularly, my invention relates to trackway circuits and apparatus whereby systems of this type may be applied to single track railways over which traffic moves in both directions.

In one system of the type mentioned, it has been proposed to employ the usual track circuit current, that is, the current which energizes the track relays, as one of the currents for controlling the train-carried governing apparatus, the train governing apparatus being controlled by this current through the medium of receiving appliances at the front end of the train. When this is done, it is obvious that the source of track circuit current must always be connected across the track rails ahead of a train. This requirement is readily met in double track railways, wherein traffic on each track moves in one direction only, because the source of track circuit current for each track section is then usually connected across the rails at the exit end of the section. In the case of a single track railway, however, this standard practice cannot be followed, because a train entering a track section at the end at which the source of current is located would obviously shunt such current away from its own receiving appliances. One feature of my invention, then, is the provision of means for connecting a source of track circuit current with the rails at one end or the other of a section depending on the direction in which the train is moving.

It has also been proposed, in systems of the type mentioned, to supply a second, or "line circuit current," to the trackway,

which current coacts with the track circuit current to control the train governing apparatus. The supply of this traffic controlling current to the track rails is controlled by traffic conditions in advance, and so for single track systems there must be two such sources of current for each section, and two sets of devices for controlling its supply to the rails of the section. Another feature of my invention, then, is the provision of means for each section for selecting the devices for controlling the supply of this current in accordance with the direction in which a train is moving.

I will describe two forms and arrangements of track-way apparatus embodying my invention, and will then point out the novel features thereon in claims.

In the accompanying drawings, Figure 1 is a diagrammatic view showing one form and arrangement of trackway apparatus embodying my invention, and Fig. 2 is a modification of the apparatus shown in Fig. 1, and also embodying my invention.

Referring first to Fig. 1, the reference characters 2 and 2^a designate the track rails of a stretch of railway track W over which traffic moves in both directions. These rails are divided by insulated joints 3 into a plurality of successive sections A—B, B—C etc.

Located at the junction of each two adjacent sections is a source of track circuit current and a track relay. As here shown, each source of track circuit current is a track transformer designated E with an exponent corresponding to the location, the secondary of which is at times connected across the rails of one adjacent section, and at times across the rails of the other adjacent section, as hereinafter explained. The primary of each transformer E is supplied with current from the secondary of another transformer designated D with a suitable exponent, pole-changers P and P^a being interposed between the two transformers as hereinafter explained. The primary of each transformer D is connected with a transmission line F which is constantly supplied with alternating current by a generator G.

Each track relay is designated by the ref-

erence character T with an exponent corresponding to the location. As here shown, each of these relays is of the polyphase motor type, comprising (see relay T^B) two stator windings 4 and 5, a rotor 6, and contacts 7, 8 and 9 operated by the rotor. The stator winding 5 is constantly supplied with current from the secondary of the adjacent transformer D , the connection being obvious from the drawing. The other stator winding 4 is at times connected with the rails of one adjacent track section, and at other times with the rails of the other adjacent section, as hereinafter explained. Each relay is responsive to reversals of the relative polarity of the current supplied to the track winding 4; when the track current is of one relative polarity, which I will term "normal", the relay contacts are swung to the right, and when the track current is of the opposite or "reverse" relative polarity the relay contacts are swung to the left. The control of the track current polarity will be explained hereinafter.

The connections of the track relays and track transformers to the rails of the several sections are controlled by traffic direction relays, one of which is located at each junction of adjacent track sections, and each of which is designated H with an exponent corresponding to the location. As here shown, each of these relays is of the polyphase motor type, comprising (see relay H^B) two stator windings 11 and 12, a rotor 10, and contacts operated by the rotor. The stator winding 11 is constantly supplied with current from the secondary of the adjacent transformer D , while the other winding 12 is supplied with current of one relative polarity or the other by means which I will explain hereinafter. The contacts of this relay are swung to the right when the winding 12 is supplied with current of one relative polarity which I will call "normal," and to the left when winding 12 is supplied with current of the opposite relative polarity which I will call "reverse."

Considering now the apparatus at location B , it will be observed that as shown in the drawing the traffic direction relay H^B is energized in normal direction; that is, the contacts of this relay are swung to the right. The secondary of track transformer E^B is then connected across the rails of section $A-B$ to the left of this location, the connection being from the secondary or transformer E^B , through wire 13, right-hand point of contact 14 of relay H^B , wires 15 and 16 to the lower rail 2^a , and from the upper rail 2, through wire 17, right-hand point of contact 18 of relay H^B , wire 19, and reactance 20 to the secondary of transformer E^B . While traffic direction relay H^B is energized in this direction, winding 4 of track relay T^B is connected across the rails of sec-

tion $B-C$ to the right of location B , the connection being from winding 4, through wire 27, right-hand point of contact 28 of relay H^B , wire 22, to the lower rail 2^a , and from the upper rail 2, through wire 23, right-hand point of contact 24 of relay H^B and wires 29 and 30 to winding 4 of the track relay. When relay H^B becomes energized in the reverse direction, the secondary of transformer E^B is disconnected from section $A-B$ and is connected across the rails of section $B-C$, the connection being from the secondary of this transformer, through wire 18, left-hand point of contact 14, wires 21 and 22 to rail 2^a , and from rail 2 through wire 23, left-hand point of contact 24, wire 25 and reactance 26 to the secondary of transformer E^B . At such times the track winding 4 of track relay T^B is disconnected from section $B-C$ and connected across the rails of section $A-B$, the path being from winding 4, through wire 27, left-hand point of contact 28 of relay H^B , wires 31 and 16 to the lower rail 2^a , and from the upper rail 2, through wire 17, left-hand point of contact 18, and wire 30 to winding 4 of the track relay.

The control of the track circuit apparatus at each of the other locations A and C is the same as that of the apparatus at location B . It will be seen, therefore, that when the traffic direction relays H are energized in normal direction a track transformer is connected with the rails at the right hand end of each section and a track relay is connected with the rails at the left hand end of each section, and that when the traffic direction relays are energized in reverse direction a track transformer is connected with the rails at the left hand end of each section and a track relay is connected with the rails at the right hand end of each section.

Traffic through the stretch of track from left to right is governed by a series of signals S^A_1 , S^B_1 , and S^C_1 , while traffic from right to left is governed by a series of signals S^A_2 , S^B_2 , and S^C_2 . As here shown, each signal is of the three-position semaphore type, arranged to indicate "stop," "caution" or "proceed," according as the semaphore is in the horizontal, inclined or vertical position. Each signal is located at the entrance end of the section through which it governs traffic, and hence it will be seen that there are two signals at each section junction or "location," one for governing traffic through the track section lying to the right of the location and the other for governing traffic through the track section lying to the left of the location.

One signal or the other at each location is placed under control of the track relay at the same location according as the corresponding traffic direction relay is energized.

in normal or reverse direction, this being accomplished by a contact on the traffic direction relay. Considering location B for example, when traffic direction relay H^B is energized in normal direction as shown, signal S^B_1 , which governs traffic to the right from this location, is placed under the control of track relay T^B . The caution indication circuit for this signal, which is open in the drawing, is then from the secondary of transformer D^B , through wires 39 and 32, right-hand point of contact 33 of relay H^B , wire 34, left-hand point of contact 7 of track relay T^B , wire 35, operating mechanism of signal S^B_1 , and wires 36, 37 and 38 to the secondary of transformer D^B . This circuit is, of course, closed only when track relay T^B is energized in the reverse direction. The proceed indication circuit for signal S^B_1 , shown closed in the drawing, is the same as the caution indication circuit, except that it includes the right-hand point of track relay contact 7 and wire 40. When traffic direction relay H^B is energized in reverse direction, signal S^B_1 is placed under the control of track relay T^B , the caution indication circuit being from the secondary of transformer D^B , through wires 39 and 32, left-hand point of contact 33, wire 41, left-hand point of track relay contact 8, wire 42, operating mechanism of signal S^B_1 , and wires 43, 37 and 38 to the secondary of transformer D^B . The proceed indication circuit, which is closed when track relay T^B is energized in normal direction, is the same as the caution indication circuit, except that it includes the right-hand point of track relay contact 8 and wire 44.

The two signals at each location are controlled in the same manner as the signals at location B.

Each pole-changer P' is operated by the adjacent signals S_1 , and each pole-changer P^2 is operated by the adjacent signal S_2 , the operation in each instance being such that the pole-changer is in the "reverse" position when the signal indicates stop, and in the "normal" position when the signal indicates caution or proceed. The control of the polarity of the track circuit current by these pole-changers is such that when a signal is in the caution or the proceed position (the opposing signal being at stop), current of normal polarity is supplied to the track rails of the section immediately in the rear of such signal; but that when a signal is in the stop position (the opposing signal also being at stop), current of reverse polarity is supplied to the rails of such section.

It will be seen from the foregoing that in so far as the apparatus thus far described is concerned, there are two complete signaling systems for the track W, one for governing traffic in one direction and the

other for governing traffic in the other direction. One or the other of these systems is placed in operation according as the traffic direction relays H are energized in normal or reverse direction. When these relays are energized in normal direction, the control and operation of the signals governing traffic toward the right is in accordance with standard practice for railways having two or more tracks, and when the traffic direction relays are energized in the reverse direction the same thing is true as to the signals governing traffic toward the left. In view of the fact that the operation of automatic signals on double track roads is thoroughly understood by those skilled in the art, it is believed that no further explanation of the operation of the apparatus thus far described is required.

Each track section is provided with two line circuits which I will term the right-hand circuit and the left-hand circuit, respectively. As shown in Fig. 1, each line circuit includes the two track rails in multiple, the current being supplied to the rails of each section through resistances 45, 46, 47 and 48, each of which is connected across the two rails. Considering section B-C specifically, when traffic direction relay H^C is energized in normal direction as shown in the drawing, the right-hand line circuit is from secondary 49 of transformer R^C , through wire 50, right-hand point of contact 51 of relay H^C , wire 52, contact Q^C_1 , operated by signal S^C_1 , wires 53 and 54 to the middle point of resistance 48, thence through the two track rails in multiple to resistance 47, and from the middle point of this resistance through wires 55 and 56 to secondary 49 of transformer R^C . The primary winding of transformer R^C is constantly supplied with current from the secondary of the adjacent transformer D^C . Circuit controller Q^C_1 is so arranged as to be closed when signal S^C_1 indicates proceed or caution, but open when this signal indicates stop. It will be seen, therefore, that when relay H^C is energized in the normal direction, the supply of current to the right-hand line circuit for section B-C is controlled by traffic conditions to the right of this section.

The right-hand line circuit for track section B-C is provided with a branch around circuit controller Q^C_1 , which branch passes from wire 50 through the left-hand point of contact 51 and wire 58 to wire 54. This branch is closed when the traffic direction relay H^C is energized in reverse direction, and so it will be seen that at such time current is supplied to the right-hand line circuit of section B-C regardless of traffic conditions extraneous to this section.

When traffic direction relay H^B is energized in the normal direction, the left-hand

- line circuit for track section B—C is from secondary winding 59 of transformer R^b, through wires 60 and 55 to the middle point of resistance 47, then through the two track rails in multiple to resistance 45, and from the middle point of this latter resistance, through wires 62 and 70, right-hand point of contact 65 of relay H^b and wire 66 to secondary 59 of transformer R^b. When relay H^b is energized in normal direction then, the left-hand line circuit for section B—C is supplied with current regardless of traffic conditions extraneous to the section. When relay H^b is energized in reverse direction, however, the supply of current to this left-hand line circuit is placed under the control of a circuit controller Q^b₂ operated by signal S^b₂. Assuming now that relay H^b is in reverse position and that signal S^b₂ is 15 in the proceed or caution position, the left-hand line circuit then passes from secondary 59 of transformer R^b, through wires 60 and 55, resistance 47, track rails 2 and 2', resistance 45, wires 62 and 63, circuit controller Q^b₂, wire 64, left-hand point of contact 65, and wire 66 to secondary 59 of transformer R^b. At such times therefore, current is supplied to the left-hand line circuit throughout its entire length. Assuming 20 now that relay H^b is in reverse position and that signal S^b₂ indicates stop, line circuit current is supplied to the rails of section B—C only between resistances 46 and 47, the left-hand line circuit then being from secondary 59 of transformer R^b, through wires 60 and 55, resistance 47, rails 2 and 2', resistance 46, wire 67, circuit controller Q^b₂, wire 64, left-hand point of contact 65, and wire 66 to secondary 59 of transformer R^b. 25
- The line circuits for section A—B are exactly the same as those for section B—C. The traffic direction relays H are controlled by a manually operable lever L located at a suitable point, such as in a signal tower. This lever L actuates two contacts 30 71 and 72, which, in turn, govern a circuit in which the windings 12 of the relays H are included in series. These contacts 71 and 72 constitute a pole-changer, so that the traffic direction relays are energized in one direction or the other according as the lever L is in one extreme position or the other. When the lever L is in the position shown in the drawing, which I will term the normal position, the circuit for the traffic direction relays is from the secondary of a transformer D^r, through wires 73 and 74, contact 71, wire 75, winding 12 of relay H^c, wire 76, winding 12 of relay H^b, wire 77, winding 12 35 of relay H^a, wire 78, contact 72, and wires 79 and 80 to the secondary of transformer D^r. The relative polarity of the current thus supplied to winding 21 of each relay H is such that this relay is energized in the 40 normal direction. When lever L is thrown to the reverse position, the controlling circuit for the traffic direction relays passes from the secondary of transformer D^r, through wires 73 and 81, contact 72, wire 78 and thence as before through winding 12 of each relay to wire 75, then through contact 71, and wires 82 and 80 to the secondary of transformer D^r. The relative polarity of the current supplied to winding 12 of each relay H is then such that these relays become energized in the reverse direction. The primary of transformer D^r is constantly supplied with current from the transmission line F.
- In order to prevent the operator from changing the direction of traffic while the track is occupied, lever L is provided with a locking device comprising a segment 83 fixed to the lever, a locking dog 84, and a magnet M for controlling this dog. When magnet M is energized, segment 83 is released so that the lever L may be operated at will, but when the magnet M is deenergized and the lever L occupies either extreme position, it is locked in such position. Magnet M is controlled by contact 9 of each track relay T, the circuit being from the + terminal of a suitable source of current, through wire 85, contact 9 of track relay T^a, wire 87, contact 9 of track relay T^b, wire 88, contact 9 of track relay T^c, wire 89, winding of magnet M, and wire 90 to the — terminal of the same source of current. Each contact 9 is closed when the corresponding relay is energized in normal or reverse direction but open when the relay is deenergized. It follows, therefore, that when a train occupies any part of the stretch of track lever L is locked in the position which it then occupies.
- Before explaining the operation of the system as a whole, it should be pointed out that the trackway apparatus here shown is intended for coöperation with train-carried governing apparatus which operates in the following manner. When a train is on a portion of track which is supplied with track circuit current of normal polarity and also with line circuit current, the governing apparatus permits the train to travel at high speed, such as 65 miles per hour. When the portion of track occupied by the train is supplied with track circuit current of reverse polarity and also with line circuit current, the governing apparatus prevents the train from proceeding at more than intermediate speed, such as 35 miles per hour. When the train enters a portion of track from which the supply of either track circuit current or line circuit current is discontinued, the governing apparatus prevents the train from proceeding at more than a low speed, such as 10 miles per hour. One form of governing apparatus which will coöperate in this manner with the track-

way apparatus here shown, is illustrated and described in an application filed in the United States Patent Office by me, on Nov. 1, 1918, Serial No. 263607, for railway traffic controlling systems.

The operation of the apparatus shown in Fig. 1 is as follows:

I will first assume that the traffic direction relays H are energized in normal direction, that the stretch of track shown in the drawing is unoccupied, and that a train moving toward the right enters the stretch. As this train enters section A-B, it deenergizes track relay T^A , so that the contacts of this relay move to their intermediate positions. The opening of the upper contact causes signal S^A_1 to move to the stop position. Inasmuch as signal S^B_1 is in the proceed position, track circuit current of normal polarity is supplied to the rails of section A-B from transformer E^B . Line circuit current is, of course, supplied to the left-hand line circuit for this section, and such current is also supplied to the right-hand line circuit for this section, because of signal S^B_1 being in the proceed position. It follows, therefore, that the train can proceed through section A-B at a speed not exceeding 65 miles per hour. The operation of the apparatus in section B-C, as the train passes through this section, is the same as that of the apparatus in section A-B.

I will now assume that while the first train is in section B-C, a second train enters section A-B. Signal S^B_1 is then at stop, so that track circuit current of reverse polarity is supplied to the rails of section A-B. Contact Q^B_1 is open, so that the right-hand line circuit for section A-B is open. Line circuit current is supplied to the rails of this section, however, between resistances 45 and 47, owing to the fact that traffic direction relay H^A is energized in normal direction. The second train will, therefore, incur a brake application if it exceeds a speed of 35 miles per hour between resistances 45 and 47, and if it exceeds a speed of 10 miles per hour between resistances 47 and 48. If the second train passes signal S^B_1 , while section B-C is still occupied, it will fail to receive track circuit current, because such current is shunted by the wheels and axles of the first train, and, consequently, the second train will still be compelled to proceed at a speed not exceeding 10 miles per hour.

When traffic direction relays H are energized in reverse direction, each signal S_1 , governing traffic toward the right, will move to the stop position, and each signal S_2 , governing traffic toward the left, will move to the proceed position. Line circuit current is then supplied to the right-hand line circuit of each section, regardless of

traffic conditions extraneous to the section; while current is supplied to the left-hand line circuit throughout the entire length of such circuit if the signal for the section next in advance indicates caution or proceed, but only from resistance 47 to resistance 46 in the event that the signal for the section next in advance indicates stop. With this explanation, the operation of the apparatus during the passage of a train moving toward the left will be obvious in view of the foregoing explanation concerning the passage of a train moving toward the right.

It should be pointed out that resistance 47 for each section is connected across the rails at least maximum braking distance from the right-hand end of the section for trains moving at the intermediate speed of 35 miles per hour. Similarly, each resistance 46 is connected across the rails at least maximum braking distance from the left-hand end of the section for trains moving at the same speed. In the event that the block is short, it is obvious that the two resistances 46 and 47 may be replaced by a single resistance connected across the rails at substantially the middle point of the section. The left-hand line circuit for such section would then be controlled in exactly the same way as the right hand line circuit for section B-C.

Referring now to Fig. 2, the apparatus is exactly the same as that shown in Fig. 1, except for the circuits which supply the line current. In Fig. 2 each section is provided with three line circuits which may be termed the right-hand circuit, the middle circuit, and the left-hand circuit. Each of these line circuits includes an auxiliary conductor extending along the track, instead of the track rails themselves as in Fig. 1. Considering track section B-C, for example, when traffic direction relay H^C is energized in normal direction, as shown in the drawing, the right-hand line circuit is from the left-hand secondary 49 of transformer R^C , through wires 91 and 100, auxiliary conductor 92, wires 93 and 94, circuit controller Q^C_1 , and wires 95 and 96 to the secondary 49 of transformer R^C . Inasmuch as circuit controller Q^C_1 is closed only in the proceed and caution positions of signal S^C_1 , it follows that current will be supplied to the auxiliary conductor 92 only when the section to the right of location C is unoccupied.

The middle line circuit for section B-C is from the secondary 49 of transformer R^C , through wires 91 and 97, auxiliary conductor 98, and wires 99 and 96 to the secondary 49 of transformer R^C . This circuit includes no contacts, and, consequently, line circuit current is constantly supplied to the auxiliary conductor 98.

The left-hand line circuit for track section B-C, when traffic direction relay H^C is

is energized in the normal direction as shown, is from the right-hand secondary of transformer R^B , through wires 91^a, 95^a, 96 and 105, right-hand point of contact 104 of traffic direction relay H^B , wires 103 and 107, auxiliary conductor 101, and wire 100^a to the secondary 59 of transformer R^B . It will be seen, therefore, that when the traffic direction relay H^B is energized in the normal direction as shown, line circuit current is supplied to the left-hand line circuit for section B—C regardless of traffic conditions extraneous to this track section.

Assuming now that the traffic direction relays H^B and H^C are reversed, it is, of course, obvious that no change occurs in the middle line circuit for section B—C. The right-hand line circuit for this section is, however, removed from control by circuit controller Q^C_1 , through the medium of a shunt which passes from wire 93 through wire 106, left-hand point of contact 104 of track relay H^C , and wire 105 to wire 96. It follows that line circuit current is then supplied to auxiliary conductor 92, regardless of traffic conditions extraneous to section B—C. The left-hand line circuit as traced above becomes open at contact 104 of traffic direction relay H^B , so that the circuit then passes from wire 91^a through wires 95 and 108, circuit controller Q^B_2 , and wires 107^a, 107, auxiliary conductor 101, and wire 100^a to the secondary 59 of transformer R^B . It follows that current is then supplied to this line circuit only when section A—B is unoccupied.

The apparatus shown in Fig. 2 is adapted for coöperation with suitable train-carried apparatus such, for example, as that shown in an application by me, filed on March 4, 1918, Serial No. 220172.

The two auxiliary conductors 92 and 101 are preferably of the same length, and this length is equal to or greater than the maximum braking distance for trains traveling at an intermediate speed, such as 35 miles per hour.

The operation of the apparatus shown in Fig. 2 will be understood in the light of the operation of Fig. 1 explained hereinbefore, and, consequently, it is believed that no further discussion of Fig. 2 is required.

Although I have herein shown and described only two forms of trackway apparatus embodying my invention, it is understood that various changes and modifications may be made therein within the scope of the appended claims without departing from the spirit and scope of my invention.

Having thus described my invention, what I claim is:

1. In combination, a stretch of railway track over which traffic moves in both directions, said stretch being divided into a plurality of successive sections, a source of alternating current and a track relay at the junction of each two sections, means at each junction for connecting the adjacent source with the rails of one section and the adjacent relay with the rails of the other section, or the source with the rails of the latter section and the relay with the rails of the former section, and signals for the sections controlled by said track relays.

2. In combination, a stretch of railway track over which traffic moves in both directions, said stretch being divided into a plurality of successive sections, a source of alternating current and a track relay at the junction of each two sections, means at each junction for connecting the adjacent source with the rails of one section and the adjacent relay with the rails of the other section, or the source with the rails of the latter section and the relay with the rails of the former section, and signals for the sections controlled by said track relays.

2. In combination, a stretch of railway track over which traffic moves in both directions, said stretch being divided into a plurality of successive sections, a source of alternating current and a track relay at the junction of each two sections, means at each junction for connecting the adjacent source with the rails of one section and the adjacent relay with the rails of the other section, or the source with the rails of the latter section and the relay with the rails of the former section, means for controlling said last-mentioned means from a central point, and signals for the sections controlled by said track relays.

3. In combination, a stretch of railway track over which traffic moves in both directions, said stretch being divided into a plurality of successive sections, a source of alternating current and a track relay at the junction of each two sections, means at each junction for connecting the adjacent source with the rails of one section and the adjacent relay with the rails of the other section, or the source with the rails of the latter section and the relay with the rails of the former section, a signal adjacent each end of each section for governing traffic into the section, and means at each junction for placing the adjacent signal for one section or the other under control of the adjacent track relay according as said relay is connected with the rails of the one section or the other.

4. In combination, a stretch of railway track over which traffic moves in both directions, said stretch being divided into a plurality of successive sections, a source of alternating current and a track relay at the junction of each two sections, a traffic direction relay at each junction and each arranged to be energized in normal and reverse direction, means controlled by each traffic direction relay when energized in normal direction for connecting the adjacent source with the rails of one section and the adjacent track relay with the rails of the other section and for connecting the track relay with the rails of the former section and the source with the rails of the latter section when energized in reverse direction, means for controlling said traffic direction relays from a central point, and signals for the sections controlled by said track relays.

5. In combination, a stretch of railway track over which traffic moves in both directions,

- said stretch being divided into a plurality of successive sections, a source of alternating current and a track relay at the junction of each two sections, a traffic direction relay at 5 each junction and each arranged to be energized in normal and reverse direction, means controlled by each traffic direction relay when energized in normal direction for connecting the adjacent source with the rails of 10 one section and the adjacent track relay with the rails of the other section and for connecting the track relay with the rails of the former section and the source with the rails of the latter section when energized in reverse direction, means for controlling said 15 traffic direction relays from a central point, a signal adjacent each end of each section for governing traffic into the section, and means controlled by each traffic direction relay for placing the adjacent signal for one section or the other under control of the adjacent track relay according as said track relay is connected with the rails of the one section or the other. 20
6. In combination, a stretch of railway track over which traffic moves in both directions, said stretch being divided into a plurality of successive sections, a source of alternating current at the junction of each 25 two sections, and means for connecting each source across the rails of one adjacent section or the other. 30
7. In combination, a stretch of railway track over which traffic moves in both directions, said stretch being divided into a plurality of successive sections, a source of alternating current at the junction of each two sections, and means controlled from a central point for connecting each source across 35 the rails of one adjacent section or the other. 40
8. In combination, a stretch of railway track over which traffic moves in both directions, said stretch being divided into a plurality of successive sections, a source of alternating current at the junction of each two sections, a traffic direction relay at each junction and each arranged to be energized in normal and reverse direction, means controlled by each traffic direction relay when 45 energized in normal direction for connecting the adjacent source of current with the rails of one adjacent section and for connecting said adjacent source with the rails of the other adjacent section when energized in reverse direction, and means for controlling said traffic direction relays from a central point. 50
9. In combination, a section of railway track over which traffic moves in both directions, a source of alternating current and a track relay adjacent each end of said section, means for at times connecting the source at one end and the relay at the other end with the rails of the section, and for at other times connecting the relay at the former end and 55 the source at the latter end with the rails of the section, and signals for the section controlled by said track relays. 60
10. In combination, a section of railway track over which traffic moves in both directions, a source of alternating current and a track relay adjacent each end of said section, means for at times connecting the source at one end and the relay at the other end with the rails of the section, and for at other times connecting the relay at the former end and the source at the latter end with the rails of the section, a signal at each 65 end of said section for governing traffic into the section, and means for placing each signal under the control of the adjacent track relay when the relay is connected with the rails of the section but not when it is disconnected from said rails. 70
11. In combination, a section of railway track over which traffic moves in both directions, two sources of alternating current one at each end of said section, and means for connecting one of said sources or the other across the track rails of said section according as traffic is to move in one direction or the other over said section. 75
12. In combination, a stretch of railway track over which traffic moves in both directions, said stretch being divided into a plurality of successive sections, a source of alternating current and a track relay responsive to reversals of current at the junction of each two adjacent sections, means for at times connecting each source with the rails of the section to the right and each relay with the rails of the section to the left, and for at other times connecting each source with the rails of the section to the left and each relay with the rails of the section to the right, two signals at each junction for governing traffic into the two adjacent sections respectively, each arranged when controlled by the adjacent track relay to indicate caution or proceed according as the relay is energized in one direction or the other, means at each junction for placing the adjacent signal for one section or the other under control of the adjacent track relay according as said relay is connected with the one section or the other, and two pole-changers at each junction operated by the two adjacent signals respectively, and connected in series for controlling the polarity of the adjacent source of current. 90
13. In combination, a section of railway track over which traffic moves in both directions, two line circuits for said section, and means for at times supplying alternating current to one line circuit regardless of traffic conditions extraneous to the section and to the other line circuit depending on traffic conditions extraneous to the section, and for at other times supplying alternating current to the first circuit depending upon traffic. 95

ditions extraneous to the section and to the second circuit regardless of traffic conditions extraneous to the section.

14. In combination, a section of railway track over which traffic moves in both directions, a left hand line circuit and a right hand line circuit for said section, means for at times supplying alternating current to the left hand circuit regardless of traffic conditions to the left of said section and to the right hand circuit depending on traffic conditions to the right of the section, and for at other times supplying alternating current to the right hand circuit regardless of traffic conditions to the right of said section and to the left hand circuit depending on traffic conditions to the left of said section.

15. In combination, a section of railway track over which traffic moves in both directions, a right hand line circuit extending from the right hand end of the section to an intermediate point located at least maximum braking distance from said end for trains moving at medium speed, a left hand circuit extending from said intermediate point to the left hand end of the section, means for supplying alternating current to said right hand circuit regardless of traffic conditions extraneous to the section when traffic toward the left is desired and for controlling said supply by traffic conditions to the right of said section when traffic toward the right is desired, and means for supplying alternating current to said left hand circuit regarding less of traffic conditions extraneous to the section when traffic toward the right is desired and for controlling said latter supply by traffic conditions to the left of the section when traffic toward the left is desired, said last-mentioned control being such that current is supplied to the left-hand circuit throughout its entire length when the section next to the left is unoccupied and only from said intermediate point to a point located at least maximum braking distance from the left hand end of the section when the section next to the left is occupied.

16. In combination, a section of railway track over which traffic moves in both directions, a left-hand line circuit and a right-hand line circuit for said section, each of said circuits including portions of the two track rails of the section in multiple, means for at times supplying alternating current to the left-hand line circuit regardless of traffic conditions extraneous to said section and to the right-hand line circuit depending on traffic conditions to the right of the section, and for at other times supplying alternating current to the right-hand line circuit regardless of traffic conditions extraneous to the section and to the left-hand line circuit depending on traffic conditions to the left of said section.

17. In combination, a section of railway

track over which traffic moves in both directions, a left-hand line circuit and a right-hand line circuit for said section, each including an auxiliary conductor parallel with the rails of the section, means for at times 70 supplying alternating current to the left-hand line circuit regardless of traffic conditions extraneous to said section and to the right-hand line circuit depending on traffic conditions to the right of the section, and for 75 at other times supplying alternating current to the right-hand line circuit regardless of traffic conditions extraneous to the section and to the left-hand line circuit depending on traffic conditions to the left of said section.

18. In combination, a stretch of railway track over which traffic moves in both directions, said stretch being divided into a plurality of sections, traffic direction relays 85 one for each section and each arranged to be energized in normal or reverse direction, means for controlling all of said relays from a central point, a right-hand line circuit and a left-hand line circuit for each section, 90 means controlled by said traffic direction relays when energized in normal direction for supplying alternating current to the right-hand line circuit for each section depending on traffic conditions to the right of 95 the section and for supplying alternating current to the left-hand line circuit for each section regardless of traffic conditions to the left of the section, and means controlled by said traffic direction relays when energized 100 in reverse direction for supplying alternating current to the right-hand line circuit of each section regardless of traffic conditions extraneous to the section and for supplying alternating current to the left-hand line circuit for each section in accordance with traffic conditions to the left of the section.

19. In combination, a section of railway track over which traffic moves in both directions; a left-hand line circuit, a right-hand line circuit, and a middle line circuit for said section; means for constantly supplying alternating current to said middle line circuit; means for at times supplying alternating current to the left-hand line circuit 115 regardless of traffic conditions extraneous to said section and to the right-hand line circuit depending on traffic conditions to the right of the section, and for at other times supplying alternating current to the right-hand line circuit regardless of traffic conditions extraneous to the section and to the left-hand line circuit depending on traffic conditions to the left of said section.

In testimony whereof I affix my signature 125
in presence of two witnesses.

LLOYD V. LEWIS.
